CALCULATING MACHINE

Carl M. Friden and John L. Moody, Oakland,
Calif., assignors to Friden Calculating Machine
Co., Inc., a corporation of California

Application July 4, 1939, Serial No. 282,767

13 Claims.

(Cl. 235—138)

This invention relates to calculating machines and is concerned more particularly with the provision of improved tens transfer mechanism for increasing the transfer capacity of a machine.

It is a general object of the invention to provide improved tens transfer mechanism for calculating machines.

Another object of the invention is to provide an improved tens transfer mechanism which can be readily incorporated to provide extra transferring orders on a machine.

Another object of the invention is to provide a tens transfer mechanism which is rapid in its operation and which positively eliminates over-thrown.

Another object of the invention is to provide an improved transfer mechanism having quiet operating characteristics.

Another object of the invention is to provide a calculating machine embodying combined tens transfer mechanism, a portion of which is of the cyclic power-operated type, and another portion of which is of the non-cyclic spring-actuated power restored type.

Other objects and advantages of the invention will be noted in connection with the following description made with reference to the accompanying drawings, in which:

Fig. 1 is a fragmentary longitudinal section through the rear portion of the machine with a part of the actuating means broken away to show the transfer mechanism. The view is taken in the plane of line 1—1 in Fig. 2.

Fig. 2 is a fragmentary plan view of the rear portion of the machine with the carriage removed.

Fig. 3 is a transverse sectional elevation taken as indicated by the line 3—3 in Fig. 2.

Fig. 4 is a transverse sectional elevation of the transfer mechanism taken in the plane of line 4—4 in Fig. 2.

Fig. 5 is a view similar to Fig. 4 but showing the transfer mechanism during a phase of its operation in which one spring-actuated transfer is completed and the next is partially completed.

Fig. 6 is a longitudinal sectional elevation taken in the plane of line 6—6 in Fig. 3 with certain parts omitted to simplify the view.

Fig. 7 is a fragmentary bottom plan view of the carriage taken as indicated by the line 7—7 in Fig. 1.

Fig. 8 is a detail view of the latch for a transfer actuator.

Fig. 9 is a detail view of one of the spring-actuated transfer actuators.

As stated above, the present invention is shown as embodied in a calculating machine of the Thomas type, as shown for example in the co-pending application of Carl M. Friden, Serial No. 724,482, filed May 8, 1934. Generally a machine

of this type includes a body in which the selecting, actuating and transfer actuating mechanisms are mounted and a shiftable register carriage, which also supports a part of the transfer mechanism.

In the calculating machine selected for purposes of illustration, the body of the calculating machine includes side frame plate 10 (Figs. 1 and 2) from which a plurality of transverse brackets 11, 12, 13 and 14 extend to a similar side plate (not shown) at the opposite or right-hand side of the machine as viewed from the front. The side plates are carried by a suitable base (not shown) in the usual manner. Brackets 11

15 and 14 support rollers 16 on which register carriage 17 is mounted for endwise shifting movement under control of any suitable means.

Carriage 17 (Fig. 1) has frame 18 in which a numeral wheel shaft 19 for each order of the register is journaled. At its upper end each shaft 19 carries numeral wheel 21 having the digits from zero to 9 inscribed thereon in the conventional manner, and at its lower end carries ten tooth numeral wheel gear 22. Intermediate its ends, each shaft 19 carries ten tooth ratchet gear 23 with which spring urged ball 24 cooperates to maintain numeral wheel 21 in adjusted position. Shaft 19 also carries resetting gear 25 for cooperation with suitable resetting means not shown.

Numerical wheels 21 (Fig. 1) are rotatable in either direction to register positive and negative values and for this purpose gear 22 has associated therewith a pair of opposed bevel gears 26, 27 formed at the ends of spool 28. The shifted positions of gears 26, 27 are controlled by transversely extending strap 29 positioned between each pair of gears 26, 27 of the various orders of the machine. Strap 29 may be mounted in a convenient manner as by one or more arms 30 for movement forwardly and rearwardly of its central neutral position shown in Fig. 1 to engage gears 26 or 27 with numeral wheel gears 22. Thus, if gears 26 are engaged with gears 22, positive actuation of the associated numeral wheels 21 will occur, and, conversely if gears 22 are engaged with gears 27, negative actuation of numeral wheels 21 is determined.

From the above description, it is seen that any increment of movement of a spool 28 will be transmitted to the associated numeral wheel 21 if either of gears 26 or 27 is placed in active position.

Means are provided in the various orders of the machine to determine the number of increments of such movement. For this purpose a bank of numeral keys 31 (Fig. 1) is provided for each order of the machine, only a part of one of such banks is shown in Fig. 1. The numeral keys 31 of each bank of the machine co-

operate with a pair of differential value selecting slides 32, 33 which are mounted for endwise shifting movement and are provided with cam surfaces of varying inclination to be set differentially in accordance with the value of the depressed numeral key. At their rearward ends, slides 32, 33 (Fig. 1) carry respective ten tooth gears 34, 35 which cooperate respectively with the two sets of stepped teeth 36, 37 on an actuating cylinder 38 of the digitation actuating mechanism.

Gears 34, 35 are mounted for sliding movement on square shaft 39 having its front end journaled in bracket 13 and extending rearwardly through bracket 12 and spool 28, and having its rear end journaled in bracket 11. Teeth 36 cooperate with gear 34 in their relatively adjusted positions to determine movement of shaft 39 for from six to nine increments, while teeth 37 and gear 35 cooperate to determine movement of shaft 39 for from one to five increments. A pair of cylinders 38 are mounted on each actuating shaft 41 for a pair of adjacent orders, the respective actuating shafts 39 of such adjacent orders being spaced to either side and above the associated actuating shaft 41 as clearly seen in Fig. 3. Each actuating shaft 41 is journaled in brackets 13 and 69 and at its front end has a bevel gear connection 42 (Fig. 1) with transverse shaft 43. Shaft 43 has its ends journaled in respective side plates and is driven cyclically from a suitable source of power such as an electric motor, or a hand crank. In the embodiment shown, one cycle of operation is effected by one rotation of shaft 43. Thus, for each rotation of shaft 43, shafts 41 and cylinders 38 also have a single rotation to cause registration of the number selected by the depressed numeral keys 31 on the associated numeral wheels 21.

Means are provided for preventing overthrow of the numeral wheels at the end of an actuation thereof and for this purpose the two sets of stepped teeth 36, 37 (Fig. 1) of each cylinder 38 are located with their last active teeth in alignment and there is associated with each shaft 39, a Geneva wheel 46 (Figs. 1 and 3) mounted thereon for rotation therewith, and associated with each Geneva wheel 46 is a locking disc 47 on an actuating shaft 41 and having a recessed portion 48 extending around its periphery for a distance corresponding to the distance occupied by teeth 36 on the associated cylinder 38. Each Geneva wheel 46 (Fig. 4) has ten concave faces for cooperation with the associated disc 47 so that for each increment of movement imparted to shaft 39 and Geneva wheel 46 by one of teeth 36 or 37, one of the faces is positioned for cooperation with associated disc 47. The trailing edge of recessed portion 48 moves into engagement with Geneva wheel 46 immediately after the last active tooth of teeth 36, 37 has actuated one of gears 34 or 35 so that the associated shaft 39 and, consequently, the associated numeral wheel 21, are positively locked against further rotation. To center shaft 39 and Geneva wheel 46 in position after movement thereof, shaft 39 carries ten tooth ratchet gear 49 (Fig. 1) adjacent frame bracket 11 which has spring-pressed ball 50 mounted therein for cooperation with gear 49.

Each pair of locking discs 47 for adjacent orders of the machine are mounted on actuating shaft 41 in axially offset relation, in the same manner and for the same purpose as the similar

mounting of the associated actuating cylinders 38.

Cyclically operable transfer mechanism of conventional construction is provided for cooperation with the actuating cylinders described above and generally such transfer mechanism comprises tripping means associated with each numeral wheel, except that of highest order, for enabling a drive connection from a transfer actuator to the numeral wheel of next higher order, so that such next higher order numeral wheel receives one increment of movement when the numeral wheel of lower order passes from 9 to 0 or 0 to 9. The sign character of the transferred increment is determined in the same manner as the sign character of the digitation increments.

To effect the tripping of a transfer, each numeral wheel shaft 19 (Figs. 1 and 7) is provided with single tooth gear 51 immediately below carriage frame 18 for cooperation with tripping lever 52, pivoted at 53 in frame 18 and yieldably held therein by spring-pressed ball 54 engaging a slightly off-center seat in pivot 53. Lever 52 has extension 55 (Fig. 7) positioned in the path of single tooth gear 51 of one order, so that when the numeral wheel passes from 9 to 0 or 0 to 9, extension 55 is engaged by the tooth of gear 51 and lever 52 is rocked in a clockwise direction as viewed in Fig. 7, the limit of such movement being determined by the engagement of face 55a of extension 55 with the next adjacent tripping lever 52. The clockwise rocking is against the urgency of spring-pressed ball 54 which yieldably maintains the lever in the position shown in Fig. 7.

Lever 52 is also provided with arm 56 extending into the next higher order of the machine and normally engaging lever 52 of such order adjacent to its pivot 53. Arm 56 has bent end 57 (Fig. 1) which extends downwardly and engages rearwardly of annular flange 58 of gear hub 59. Hub 59 carries transfer gear 61 and is slidably mounted on shaft 39 so that rocking movement of tripping lever 52 results in shifting hub 59 and gear 61 forwardly of the machine to position gear 61 in operative relation with respect to the transfer actuator therefor. Single tooth cyclic transfer actuator 62 (Figs. 1 and 4) for gear 61 is suitably mounted with actuator 62a of the adjacent lower order by locking discs 47. To enable movement of shaft 39 by operation of actuator 62 and to prevent overthrow thereafter, each locking disc 47 is provided with a transfer notch 63 (Fig. 3) spaced from recessed portion 48 by an interposed solid portion 64 of disc 47.

From the above description it is seen that each time a transfer is determined in one order of the machine, gear 61 of the next higher order is moved into active position to be subsequently operated by the associated transfer actuator 62.

Means are provided for resiliently maintaining gear 61 in either shifted position thereof and associated with such maintaining means is a restoring cam, which operates with each pair of adjacent gears 61. Gear hub 59 (Fig. 1) has a second annular flange 66 which extends between spaced annular flanges 67 of shaft 68, which is slidably mounted in transverse member 69 secured on bracket 12 and spaced therefrom, and transverse member 71 spaced from member 69 and suitably supported on the frame of the machine. Shaft 68 is suitably maintained resiliently in either shifted position thereof. It will be noted that when gear 61 is moved to operative position the forward end of shaft 68 will project beyond member 69 and into the path of restoring cam 72

(Figs. 1 and 4) preferably formed integrally with actuator 62a of each pair of associated transfer actuators. It will be seen that the successive pairs of actuators 62, 62a on the remaining actuating shafts 41 are spaced apart an angular distance to provide for successive operation of the transfer actuators from the lowest to the highest order.

The above described mechanism is all of conventional construction being described and claimed in the co-pending application of Carl M. Friden, Serial No. 75,307, filed April 20, 1936. Usually, one or more extra transfer orders of the character described above are provided in orders which do not have any digitation actuation associated therewith. However, the number of such orders which can be utilized in a 360° cycle is limited, and the present invention is concerned with provision of additional extra transfer orders which are of a character to extend the transfer capacity of the machine without requiring the same amount of time in the cycle as the cyclically timed transfer mechanism of the type described above.

The non-cyclic transfer mechanism comprises generally a spring-urged latched transfer actuator in each order and means associated therewith for tripping the latch to enable the transfer operation, and for subsequently restoring the actuator to restrained position by power. The restoring operation is preferably effected during the first part of the next cycle of operation.

Referring to Fig. 2, it will be noted that the two left-hand or highest order spools 28 are mounted on square shafts 75 similar in all respects to shafts 39, but ending at bracket 12. Each shaft 75 (Figs. 3, 4 and 6) carries a ten-tooth ratchet gear 76 for receiving transferred increments, and has associated therewith centering pawl 77 pivoted on stud 78 on brackets 12 and 69, and urged into engagement with gear 76 by spring 79. Springs 79 are tensioned between respective centralizing pawls 77 and levers 83 and 84, respectively. Respective gears 76 (Fig. 4) also have associated therewith respective actuating pawls 81 pivoted at 82 on respective levers 83, 84 and urged by respective springs 86 against respective stop pins 87 on actuating levers 83 and 84. Levers 83 and 84 are pivoted on studs 78 and are similar except that lever 83 is provided with lower arm 88 for a purpose later described.

Levers 83 and 84 (Fig. 4) are urged in a clockwise direction (as viewed in Fig. 4) by respective springs 89 tensioned between respective ears 91 thereof and studs 92 on bracket 12. The operative movement of levers 83 and 84 under the urgency of their springs 89 is prevented by respective spring-urged latch pawls 93 (Figs. 2 and 3) pivoted by studs 94 on bracket 12 and having latch arms 96 for engagement with upper ends 97 of levers 83 and 84. Pawls 93 also have bent ends 98 on one arm for engagement by respective springs 99 also connected to studs 94. Thus, levers 83 and 84 are latched normally in inactive position.

To release the latches, each pawl 93 (Fig. 2) has curved arm 101 for cooperation with an aligned end 57 of the transfer lever 52 of next lower order. Thus, when such lower order numeral wheel passes from 9 to 0, or 0 to 9, latch 93 is moved to inactive position and lever 83 (for example) is free to move under the influence of its spring 89, so that pawl 81 will move the associated gear 76 one tooth spacing. The extent

of throw of pawls 81 is determined by respective stop extensions 102 of levers 83 and 84 engaging against respective studs 92. Clockwise movement of either of levers 83 and 84 serves to relieve the tension of the associated spring 79 and thereby effects release of the associated centralizing pawl 77.

Referring to Fig. 4 it will be noted that the rounded end of pawl 81 is cooperatively related to the point of the cooperating tooth of ratchet gear 76 so that during the initial movement of the gear the pointed end of pawl 81 is inactive and the gear is being actuated at its greatest radius. As the movement proceeds the line of contact between the pawl and the gear tooth moves radially inward until the pointed pawl end engages the base of the tooth as shown with right-hand pawl 81 in Fig. 5. Thus, the actuation of gear 76 starts rapidly and slows down gradually until the movement is completed as shown with left-hand pawl 81 in Fig. 5. Pawls 81 also act to prevent overthrow in the position of left-hand pawl 81 in Fig. 5.

After transfer operation of levers 83 and 84 and pawls 81 thereon, power driven restoring means becomes operative during the first part of the next cycle of operation to restore the levers to inactive position. For this purpose, cam 106 (Fig. 3) is mounted on left-most shaft 41 for operative engagement with roller 107 at the end of arm 88 of lever 83 so that lever 83 will be moved by cam 106 from the position shown in Fig. 5 to its latched position shown in Fig. 4. To also restore lever 84, lever 83 (Fig. 3) carries pin 108 on which one end of link 109 is pivoted, while the other end of link 109 is slotted at 110 to engage pin 111 on lever 84. During restoring movement of levers 83 and 84, pawls 81 yield and ride back over the next active teeth of respective gears 76 which are held against retrograde movement by the ends of respective centering pawls 77 which are engaged behind the related teeth of gears 76. Because of the slot 110, lever 83 can be released for transferring movement without affecting lever 84.

We claim:

1. In a calculating machine, a series of ordinal numeral wheels, power-operated cyclic transfer actuating mechanism for certain orders of said numeral wheels, spring-actuated non-cyclic transfer actuating means for others of said numeral wheels, and means controlled by said cyclic transfer mechanism for causing operation of said non-cyclic transfer means, said numeral wheels being mounted for linear ordinal shifting movement with respect to said actuating mechanism and said actuating means.

2. In a calculating machine, a series of ordinal numeral wheels, power-operated cyclic transfer actuating mechanism for certain orders of said numeral wheels, spring-actuated non-cyclic transfer actuating means for others of said numeral wheels, means controlled by said cyclic transfer mechanism for causing operation of said non-cyclic transfer means, and means driven in time with said cyclic transfer mechanism for restoring said non-cyclic transfer means to inactive position, said numeral wheels being mounted for linear ordinal shifting movement with respect to said actuating mechanism and said actuating means.

3. In a calculating machine having a series of ordinal numeral wheels and ordinal digitation actuating means for association with the lower order numeral wheels, cyclic transfer actuating

mechanism associated with at least all of said lower order numeral wheels, and spring-actuated non-cyclic transfer actuating means associated with orders of said numeral wheels higher than said lower orders, said numeral wheels being mounted for linear ordinal shifting movement with respect to said actuating mechanism and said actuating means.

4. In a calculating machine having a series of ordinal numeral wheels, plus-minus gears for selectively transmitting positive and negative increments of movement to said wheels, and a series of ordinal shafts for transmitting increments to said gears; cyclically operable transfer actuating mechanism associated with certain of said shafts, and spring-actuated transfer actuating means associated with the next higher order shaft than said certain shafts, said numeral wheels being mounted for linear ordinal shifting movement with respect to said actuating mechanism and said actuating means.

5. In a calculating machine, a pair of adjacent numeral wheels, means associated with the lower order wheel for tripping a transfer; a transfer actuator for association with said wheel of higher order, spring means urging said actuator to actuate said higher order wheel, a latch normally restraining movement of said actuator and controlled by said transfer tripping means, and means for restoring said actuator into operative engagement with said latch.

6. In a calculating machine, numeral wheels, a spring actuated transfer mechanism operable between an adjacent pair of said wheels, a ratchet wheel actuated by said transfer mechanism, centralizing means for holding said ratchet wheel in transferring position, means for restoring said transfer mechanism to actuating position, and means for rendering said ratchet centralizing means substantially ineffective with actuation of said transferring mechanism.

7. In a calculating machine, a vertical bracket, a horizontal increment transmitting shaft journaled on said bracket and extending outwardly therefrom, a ratchet wheel on said shaft and having a driving connection therewith, a transfer actuating lever pivoted on said bracket about an axis parallel to the shaft axis, an actuating pawl pivoted on said actuating lever about a horizontal axis and having its movable end disposed for engagement with the teeth of said ratchet wheel, a stop on said actuating lever, and a spring urging said pawl against said stop, a second spring urging said lever in a direction to move said pawl into engagement with said ratchet wheel to effect a one-step movement thereof, a latch pivotally mounted on said bracket about a vertical axis and having a portion operatively engaging said lever to restrain movement thereof under the urgency of said second spring, and means for oscillating said latch to release said actuating lever.

8. In a calculating machine, a bracket, an increment transmitting shaft journaled on said bracket and extending outwardly therefrom, a ratchet wheel on said shaft, a transfer actuating lever pivoted on said bracket about an axis parallel to the shaft axis, an actuating pawl movably mounted on said actuating lever, a spring urging said lever in a direction to move said pawl into engagement with said ratchet wheel, a latch mounted on said bracket and restraining said actuating lever, and a centralizer movably mounted on said bracket for movement in a direction parallel to the movement of said actu-

ating lever and a spring connected to said actuating lever and to said centralizer to control said centralizer for centralizing engagement with said ratchet wheel when said actuating lever is in its latched position.

9. In a calculating machine, a bracket, an increment transmitting shaft journaled on said bracket and extending outwardly therefrom, a ratchet wheel on said shaft, a transfer actuating lever pivoted on said bracket about an axis parallel to the shaft axis, an actuating pawl movably mounted on said actuating lever, a spring urging said lever in a direction to move said pawl into engagement with said ratchet wheel, a latch mounted on said bracket and restraining said actuating lever, a centralizing lever pivotally mounted upon an axis coincident with the axis of the transfer actuating lever and having its end disposed for engagement with the teeth of said ratchet wheel opposed to said actuating lever, and a spring connecting said actuating and centralizing lever.

10. In a calculating machine, an increment transmitting member, spring actuated transfer mechanism for imparting an increment movement to said member, a latch for holding said transfer mechanism in inoperative position, a centralizer associated with said member, and means controlled by said transfer mechanism for urging said centralizer to operative position.

11. In a calculating machine, a series of numeral wheels, a plurality of spring actuated normally latched transfer units for a plurality of adjacent orders of said numeral wheels, said numeral wheels being mounted for linear ordinal shifting movement relative to said transfer units, means shiftable with said numeral wheels for selectively enabling said units under control of said numeral wheels to effect transfer of increments from one wheel to the next higher order wheel, and means common to said transfer units for restoring any unlatched units to latched condition.

12. In a calculating machine, numeral wheels, a spring-actuated transfer actuating mechanism operable between an adjacent pair of said wheels, said mechanism including a ratchet wheel and a pawl disposed for actuating said ratchet wheel, said ratchet and said pawl being constructed and arranged whereby an end portion of said pawl spaced from the point thereof is disposed for initial engagement with a point of a tooth of said ratchet wheel whereby greater starting leverage is obtained upon initial engagement of said pawl with said wheel and whereby subsequently the point of engagement between the tooth of the ratchet wheel and the pawl is changed until the point of the pawl is seated at the base of the tooth at the end of the actuating operation.

13. In a calculating machine, a series of ordinal numeral wheels, power-operated cyclic transfer mechanism for certain orders of said numeral wheels, spring-actuated non-cyclic transfer actuating means for others of said numeral wheels, said numeral wheels being mounted for ordinal shifting movement with respect to said transfer actuating mechanism and means, and a series of transfer tripping elements mounted for shifting movement with said numeral wheels and operable thereby to control both said transfer actuating mechanism and said transfer actuating means.

CARL M. FRIDEN.
JOHN L. MOODY.
